TEMPERATURE CONTROLLING VALVE

William L. McGrath, Syracuse, N. Y., assignor to
 Carrier Corporation, Syracuse, N. Y., a corpora-
 tion of Delaware

Application October 1, 1945, Serial No. 619,610

15 Claims. (Cl. 236—1)

1

This invention relates to valve structures and more particularly to a valve structure designed for use in air conditioning systems to effect change-over from summer to winter operating conditions or vice-versa. The invention is also concerned with an air conditioning system including such valve structure.

In Carrier Patents Nos. 2,363,294 and 2,363,945, granted November 21, 1944, and November 28, 1944, respectively, there is disclosed an air conditioning system in which a volume of air is conditioned to a desired degree at a central conditioning point and is then distributed at relatively high static pressure and at relatively high velocity to a plurality of units respectively disposed in and serving a plurality of enclosures to be conditioned. The high pressure air supplied to each unit is discharged therein through nozzle formations or the like and in this manner induces a relatively great circulation of air withdrawn from the area served by the unit. Primary or conditioned air and secondary or induced air are then supplied to the area to be conditioned. The primary air may be conditioned at a central conditioning point. Heated or cooled water or other fluid is delivered to the various units from a central station to effect sensible heating or cooling of air circulating through the units as required. In such system, it is necessary to supply some form of control to produce and to maintain desired atmospheric conditions.

The chief object of this invention is to provide a new and improved valve structure. An object of this invention is to provide an improved valve structure for use in an air conditioning unit capable of satisfactory performance under different seasonal operating conditions. A further object is to provide a valve including means capable of changing the operation of the structure under different seasonal operating conditions. A still further object is to provide an air conditioning system including means whereby conditioning medium is permitted to bypass the conditioning unit in response to changes in temperature of the area or space being conditioned. A still further object is to provide an improved closure member for use in valve structures. A still further object is to provide a valve structure including a bypass passage adapted for use when the primary passage of the valve is closed to permit free flow of conditioning medium through the valve thereby obviating stagnation of conditioning medium in the valve. Other objects of my invention will be readily perceived from the following description.

This invention relates to a valve structure

which comprises in combination a housing having a passage therethrough, means for opening and closing the passage, and means for controlling the operation of said first means, said second means being operable in response to the condition of the medium entering the housing to control the operation of said first means. The change-over or control mechanism of the valve structure may be responsive to the temperature of conditioning medium entering the housing or to the hydrostatic pressure of such medium. The phrase "condition of medium entering the housing" is used to denote generally the temperature or the hydrostatic pressure of the conditioning medium entering the housing which serves to actuate the change-over mechanism. The invention also includes a closure member of specific design adapted to close the passage through the valve; such member serves to improve control characteristics and permits operation against higher differential pressures. The invention also includes a specific arrangement of elements to provide a bypass permitting free flow of conditioning medium through the housing when it is desired to prevent flow of conditioning medium to the conditioning unit.

The attached drawing illustrates a preferred embodiment of my invention, in which

Figure 1 is a sectional view illustrating the valve structure of my invention;

Figure 2 is a sectional view taken on the line 2—2 of Figure 1;

Figure 3 is a fragmentary diagrammatic view of an air conditioning system employing the improved valve structure shown in Figure 1; and

Figure 4 is a fragmentary sectional view of the valve shown in Figure 1 illustrating a modified form of valve structure.

Referring to the drawing, there is shown the valve structure 2 of my invention. Valve 2 includes a housing designated generally at 3, preferably formed in two sections for easy positioning of the various elements. The two sections of housing 3 may be secured together by any suitable fastening means as shown at 4. Inlet 5 is formed in housing 3 to permit entrance of conditioning medium to the interior of the housing. An outlet 6 is provided to permit the passage of conditioning medium from the valve 2. Inlet 5 is connected to a duct 7 from which conditioning medium may be conducted to the valve. Conditioning medium flows through valve 2 and from the outlet 6 to heat exchange member 8 of a conditioning unit 9. Conditioning medium passes through the heat exchange member 8 to a second duct 10 which returns it to a central source of

supply. A bypass 11 connects valve 2 with duct 10.

A closure member 12 is provided to engage valve seat 13 of valve 2 to close the valve to the passage of conditioning medium through outlet 6. The specific construction of closure 12 will be described hereinafter. Bell cranks 14 and 15 are provided to raise and to lower closure 12 to open and to close the passage through valve 2. Bell cranks 14 and 15 are held in position in the housing by means of pin 16 attached to the walls of housing 3, and are capable of pivoting or rotating about pin 16. A whiffle-tree 17 is provided to rotate or pivot bell cranks 14 and 15 about the pivot pin 16. One arm 17' of whiffle-tree 17 is pinned to crank 14 at point 26 while the other arm 17'' of whiffle-tree 17 is pinned to bell crank 15 at point 27. A rod 18 having one end terminating in a yoke 19 is secured to whiffle-tree 17. The opposite end of rod 18 is secured to a bellows 20; lever is advanced or withdrawn by expansion and contraction of bellows 20. Bellows 20, preferably, forms part of a regulating element responsive to the temperature of the space being conditioned.

A plate 21 carrying members 22 and 23 influences or controls the movement of bell cranks 14 and 15 and determines whether bell crank 14 or bell crank 15 is rotated by whiffle-tree 17 about pivot pin 16. Movement of plate 21 in a substantially vertical direction determines whether member 23 or member 22 is placed in position to permit or to prevent rotary movement of crank 14 or crank 15. Movement of plate 21 is controlled by means of a bellows 24.

Bellows 24 may be responsive to the temperature of conditioning medium entering the valve or it may be responsive to the hydrostatic pressure of conditioning medium entering the valve. As shown, bellows 24 may be filled with expandable fluid, as is well known in the art, which expands or contracts in response to the temperature of conditioning medium entering the valve.

Pin 16 extends through a slot in plate 21 and permits plate 21 to move freely in a substantially vertical direction in response to contraction and expansion of bellows 24 to dispose members 22 or 23 in position to limit movement of cranks 14 or 15. A stop 25 is provided rigidly fixed to the walls of housing 3 to prevent rotation of cranks 14 and 15 in one direction.

Closure member 12 includes a valve member 28 adapted to engage valve seat 29 to close the passage through valve structure 2. Member 28 is provided with a passage 30 extending from its exterior surface to an internal cavity 31 and thence to the outlet 6 of the valve. A valve seat 32 is provided in member 28 and is adapted to cooperate with an enlarged head 33 of rod 34 which serves to raise member 28 from seat 29 and to lower member 28 into engagement with seat 29 in response to rotation of bell cranks 14 or 15. A pin 35 is provided in rod 34 and is adapted to engage the ends of bell cranks 14 and 15 in order to permit rod 34 to be raised by rotation of cranks 14 or 15. As rod 34 is raised, it removes head 33 from engagement with seat 32 permitting passage of conditioning medium through the interior of member 28 and to outlet 6. Upon further movement of rod 34 in an upward direction it engages the upper portion of member 28 and moves member 28 from engagement with seat 29, thus opening the passage to the flow of conditioning medium and permitting free flow of conditioning medium through the valve.

Plug 37 extends through the wall of housing 3. Plug 37 is provided with a passage 38 to permit the flow of conditioning medium through bypass 11. An end 39 of rod 34 is adapted to cooperate with valve seat 40 of plug 37 to close passage 38 to the free flow of conditioning medium to bypass 11. Spring 41 is interposed between one end of plug 37 and a stop 42 attached to rod 34. Spring 41 holds open the passage 38 to bypass 11 while maintaining member 28 in engaging position with seat 29 to prevent passage of conditioning medium to outlet 6. As rod 34 is raised by cranks 14 or 15, end 39 of rod 34 engages valve seat 40 and closes passage 38 to free flow of conditioning medium to bypass 11 while permitting free flow of conditioning medium to outlet 6. As rod 34 is lowered, member 28 engages seat 29 and prevents passage of conditioning medium to outlet 6 while permitting flow of conditioning medium to bypass 11 through passage 38.

As pointed out above, bellows 20 forms part of a regulating control. The regulating control may be composed of a thermo sensitive element 43 and a limit regulating control 44 as well known in the art. Element 43 is connected to bellows 20 by line 45. Limit regulating control 44 is also connected to bellows 20 by line 46. Bellows 20, element 43, control 44, and lines 45 and 46 are filled with a fluid capable of expansion and contraction in accordance with the temperature of the space being conditioned. Element 43, preferably, is disposed in such space as shown in Figure 3. Any suitable fluid may be used in the closed circuit formed by such elements, for example, oil or other expandible liquids. Such control element is well known in the art and forms no part of my invention per se.

I will describe the operation of the valve under winter conditions, assuming that hot water, for example, is being passed from duct 7 to the heat exchange member 8 of conditioning unit 9. The temperature of the conditioning medium in the valve causes the fluid in bellows 24 to expand thus expanding bellows 24 and moving plate 21 downward; movement of plate 21 downward places control member 22 in position to prevent rotation of crank 15 about pin 16. Assume the temperature of the space being conditioned reflects a demand for heating. Bellows 20 contracts carrying with it rod 18 and forcing arm 17' of whiffle-tree 17, attached to crank 14, to move backward, to the left as shown in Figure 1, rotating bell crank 14 about pivot pin 16. Bell crank 15 is held in fixed position by means of stop 22 so that whiffle-tree 17 pivots about point 27 permitting arm 17' to be moved as described. Rotation of bell crank 14, which engages pin 35 of rod 34, raises rod 34 and permits conditioning medium to flow through passage 30 and cavity 31 of member 28, permitting minor flow of conditioning medium to heat exchange member 8. As bellows 20 reflects a demand for further conditioning medium, crank 14 rotates through a greater arc about pin 16 and disengages member 28 from valve seat 29 permitting a greater amount of conditioning medium to flow to heat exchange member 8.

Assume element 43 then reflects an increase in temperature in the space being conditioned causing bellows 20 to expand. Limiting member 22, of course, prevents rotation of bell crank 15. Accordingly, whiffle-tree 17 again pivots about point 27 and moves arm 17' forward, to the right as shown in Figure 1. Movement of arm

11' in a forward direction rotates bell crank 14 about pivot pin 16 permitting spring 41 to force rod 34 downward, moving member 28 downward to limit the flow of conditioning medium to heat exchange member 8. As rod 34 is raised, end 39 thereof engages valve seat 40 in plug 37 and closes bypass 11; as member 28 again moves downward into engagement with valve seat 29, spring 41 forces rod 34 downward to close outlet 6 and to open passage 38 leading to bypass 11.

Under summer operating conditions cold water, for example, is supplied to heat exchange member 8. Bellows 24, responsive to the temperature of the water entering the valve, contracts raising plate 21 and placing member 23 in position to prevent rotation of bell crank 14 about pin 16. As element 43 reflects a demand for cooling in the space being conditioned, bellows 20 expands pivoting whiffle-tree 17 about point 26 and moving arm 17" forward, to the right as shown in Figure 1. Movement of arm 17" rotates crank 15 about pin 16 to raise rod 34, opening outlet 6 to the passage of conditioning medium to heat exchange member 8. As element 43 reflects a decrease in temperature of the space being conditioned, bellows 20 contracts, again pivoting whiffle-tree 17 about point 26 and moving arm 17" rearwardly, to the left as shown in Figure 1, to rotate crank 15 about pin 16 in the opposite direction. Control member 23, prevents movement of crank 14 thus assuring movement of crank 15. Crank 15 permits rod 34 to be forced downward by spring 41 to close outlet 6 by engagement of member 28 with valve seat 29 and engagement of head 33 of rod 34 with valve seat 32 of member 28. As rod 34 is lowered, passage 30 leading to bypass 11 is again opened to permit the passage of conditioning medium through bypass 11 thus obviating the collection of stagnant water in valve 2.

In Figure 4 there is illustrated a modified form of valve structure adapted to permit the valve to operate under high pressure differences without a decrease in sensitivity. As shown in Figure 4 the end of rod 34 leading to bypass 11 is formed in the shape of a piston 47 fitting within chamber 48 leading to the bypass 11. Valve member 12 secured to the opposite end of rod 34 serves to engage valve seat 13 to close outlet 6 to the passage of conditioning medium. Piston 47 is slightly smaller in area than the main valve port 13. Since the pressure drop across the bypass piston 47 is substantially the same as the pressure drop across the main valve port 13, when the valve member is in closed position, approximately equal forces are exerted serving to move rod 34 in either direction. As rod 34 moves, the magnitude of the two forces changes to some extent but still serves to maintain the valve in balance.

My invention provides a ready and simple means for controlling the operation of air conditioning systems under summer and winter operating conditions. The valve structure of my invention permits a ready and efficient change-over from summer to winter operating conditions in an air conditioning system.

The valve structure of my invention is simple, economical and readily manufactured and installed. In addition, my invention provides an improved closure member for a valve structure which permits increased sensitivity of operation and prevents chattering of the valve. It also permits more simple and less expensive valve

elements to be provided thereby considerably decreasing the cost of the valve.

My invention provides a constant flow of conditioning medium through the valve and obviates collection of stagnant conditioning medium in the valve since the medium supplied to the valve is either passed to the heat exchange member of the conditioning unit or is permitted to flow through the valve to a bypass which returns the conditioning medium to a central source of supply.

While I have described and illustrated a preferred embodiment of my invention, it will be understood that my invention is not limited thereto since it may be otherwise embodied within the scope of the following claims.

I claim:

1. In a valve structure, the combination of a housing having a passage therethrough, means for opening and closing said passage, a whiffle-tree connected to said means, thermostatic means for actuating said whiffle-tree, and an element for controlling movement of said first means, and second thermostatic means for placing said element in a first position to control movement of said means when medium of a predetermined temperature enters the housing and in a second position to change the direction of movement of said first means when medium of a different temperature enters the housing.

2. In a valve structure, the combination of a housing having a passage therethrough, a closure in said passage, a whiffle-tree, bell cranks for moving said closure to open and to close the passage, said bell cranks being connected to said whiffle-tree and being operable in response to movement thereof, a plate, thermostatic means for moving said plate in response to the condition of medium entering the housing, members carried by said plate adapted to control movement of said bell cranks, the member placed in position to prevent movement of one of said bell cranks being determined by movement of said plate, and thermostatic means for actuating said whiffle-tree in response to a change in temperature in an area being conditioned.

3. In a valve structure, the combination of a housing having a passage therethrough, a closure in said passage, a whiffle-tree, bell cranks for moving said closure to open and to close the passage, said bell cranks being connected to said whiffle-tree and operable by movement thereof, a plate movable in response to the condition of medium entering the housing, members carried by said plate adapted to control movement of said bell cranks, thermostatic means for moving said plate to a first position in response to a predetermined condition of medium entering the housing to place one of said members in position to prevent movement of one of said bell cranks and to a second position in response to a different condition of medium entering the housing to place a second member in position to prevent movement of another bell crank, and second thermostatic means for actuating said whiffle-tree in response to a change in temperature in an area being conditioned.

4. In a valve structure, the combination of a housing having a passage therethrough, a closure in said passage, a whiffle-tree, a temperature responsive element for actuating said whiffle-tree, said element being responsive to the temperature of the space being conditioned, bell cranks connected to said whiffle-tree and operable by movement thereof, a plate, thermostatic

means for moving said plate from a first position to a second position in response to the condition of medium entering the housing, members carried by said plate adapted to control movement of said bell cranks, the member placed in controlling position being determined by the position of said plate, said closure including a member for closing said passage, said closure member having a second passage therein leading from the exterior thereof to the first passage, and a second closure member adapted to close the passage in said first closure member, each of said bell cranks as determined by said control members serving to move said second closure member to open the passage through said first closure member and upon further movement to move said first closure member to open the first passage.

5. In a valve structure, the combination of a housing having a passage therethrough, a valve member for opening and closing said passage means for moving the valve member to open and to close the passage, a whiffle-tree connected to said means, thermostatic means for actuating said whiffle-tree in response to a change in temperature in an area being conditioned, means for controlling the operation of said first means, a thermostatic element for operating said control means in response to the condition of medium entering the housing, and a passage in said housing connected to a bypass, said first means serving to open said second passage when said first passage is closed and to close said second passage when said first passage is open.

6. In an air conditioning system, the combination of an air conditioning unit containing a heat exchange member, a duct for the passage of conditioning medium to said member, a second duct for withdrawing conditioning medium from said member, a valve in said first duct to meter the amount of conditioning medium passing through said unit, said valve including a housing having a passage therethrough, a closure in said passage, a whiffle-tree, thermostatic means for actuating the whiffle-tree in response to a change in temperature in an area being conditioned, bell cranks for moving said closure to open and to close the passage, said bell cranks being connected to said whiffle-tree and operable by movement thereof, a plate, second thermostatic means for moving said plate in response to the condition of medium entering the housing, members carried by said plate adapted to control movement of said bell cranks, the member placed in controlling position being determined by movement of said plate, a passage in the housing connected to a bypass, and a bypass connecting said housing with said second duct, said closure serving to close said first duct to the passage of conditioning medium and to open said bypass to the passage of conditioning medium in response to a predetermined temperature of the space being conditioned and to close said bypass and to open said first duct to the passage of conditioning medium in response to a change in the temperature of the space being conditioned.

7. In a valve structure, the combination of a housing having a passage therethrough, a member for opening and closing said passage, movable means for actuating said member, a first thermostatic element to actuate said means in response to a change in temperature of a space being conditioned, a second member to govern movement of said means, a second thermostatic element to control the position of said second member in response to the condition of medium

entering the housing whereby said member is disposed in a first position in response to a predetermined condition of medium entering the housing and in a second position in response to a predetermined change in condition of medium entering the housing, a second passage in said housing connected to a bypass, and a second member actuated by said means for opening and closing the second passage, said means serving to open the second passage when the first passage is closed and to close the second passage when the first passage is open.

8. In a valve structure, the combination of a housing having a passage therethrough, a closure in said passage, a whiffle-tree, bell cranks for moving said closure to open and to close the passage, said bell cranks being connected to said whiffle-tree and being operable by movement thereof, thermostatic means for actuating the whiffle-tree in response to a change in temperature in an area being conditioned, a plate, a thermostatic element for moving said plate in response to the condition of medium entering the housing, members carried by said plate adapted to control movement of said bell cranks, the member placed in controlling position being determined by movement of said plate, and a second passage in said housing connected to a bypass, each of said bell cranks as determined by said control members serving to open said second passage when said first passage is closed, and to close said second passage when said first passage is open.

9. In an air conditioning system, the combination of an air conditioning unit containing a heat exchange member, a line for the passage of conditioning medium to said member, a second line for withdrawing conditioning medium from said member, a valve in said first line to meter the amount of conditioning medium passing through the heat exchange member of said unit, said valve including a housing having a passage therethrough and means for opening and closing said passage, thermostatic means for actuating said means in response to change in temperature of a space being conditioned, third means for controlling the operation of said first means, and thermostatic means for actuating said third means in response to the condition of medium entering the housing through said first line to change the direction of movement of said first means, a passage in said housing connected to a bypass, and a bypass connecting said housing with said second line, said first means serving to close said first line to the passage of conditioning medium and to open said bypass to the passage of conditioning medium in response to a predetermined temperature of the space being conditioned, and to close said bypass and to open said first line in response to a change in the temperature of the space being conditioned.

10. In a valve structure, the combination of a housing having a passage therethrough, means for opening and closing said passage, a whiffle-tree connected to said means, thermostatic means for actuating said whiffle-tree, means for controlling the operation of said first means, and a second thermostatic means for actuating said control means in response to the condition of medium entering the housing to reverse the operation of said first means.

11. In a valve structure, the combination of a housing having a passage therethrough, a valve member for opening and closing said passage,

means for moving the valve member to open and to close the passage, a whiffle-tree connected to said means, thermostatic means for actuating said whiffle-tree in response to a change in temperature of a space being conditioned, a control element, members carried by said element for controlling movement of said first means and second thermostatic means for moving said element in response to the condition of medium entering the housing to select the member placed in control position.

12. In a valve structure, the combination of a housing having a passage therethrough, a valve member for opening and closing said passage, cranks for moving said member, a first thermostatic element to actuate the cranks in response to a change in temperature of a space being conditioned, a movable member for selecting the crank to move said valve member, and a second thermostatic element to place said movable member in a position to select the crank to move said valve member, said second thermostatic element being responsive to the condition of medium entering the housing whereby in response to a predetermined condition of medium entering the housing, one of said cranks actuates said valve member to move in a direction to increase flow of medium through the housing upon an increase in temperature in a space being conditioned while in response to a predetermined change in condition of medium entering the housing a second crank actuates said valve member to move in a direction to decrease flow of medium through the housing upon an increase in temperature in a space being conditioned.

13. In a valve structure, the combination of a housing having a port therein, a valve member adapted to move from and toward the port to open and to close the port; a device including a first member and a second member for actuating said valve member, both members being connected to the valve member, and thermostatic means to actuate said members in response to a change in temperature in an area being conditioned; a movable element carrying stop members for selecting the member to actuate the valve member, and second thermostatic means for moving said element to a first position in response to a predetermined condition of conditioning medium entering the housing to prevent movement of said first member while permitting movement of said second member and to a second position in response to a predetermined change in condition of medium entering the housing to prevent movement of said second member while permitting movement of said first member.

14. In a valve structure, the combination of a

housing having a port therein, a valve member adapted to move from and toward the port to open and close the port, a plurality of elements connected to said valve member to open and to close the port, a first thermostatic element to actuate said elements in response to the temperature of an area being conditioned, a movable member for selecting the element to actuate the valve member, and a second thermostatic element responsive to the condition of medium entering the housing to place the movable member in a first position to select one of the elements to actuate the valve member when medium of a predetermined condition enters the housing, and in a second position to select a second element to actuate the valve member when medium of a different condition enters the housing.

15. In a temperature responsive valve for regulating the flow of heat transfer medium to an air conditioning unit, the combination of a valve casing having an outlet port and a bypass port for heat transfer medium, a valve stem aligned with and positioned between said ports, said stem having a valve end portion cooperable with said bypass port, a double valve member on said stem cooperable with said outlet port, said valve member having a hollow main portion containing a valve seat and having a secondary valve portion cooperable with said seat and fixed on said stem, said main portion including a member slidably receiving said stem and engageable by said secondary portion to lift said main portion, a whiffle-tree, means for transmitting movement of the whiffle-tree to said valve stem, thermostatic means for actuating said whiffle-tree, members governing movement of the transmitting means, and a second thermostatic means for actuating said governing members in response to the condition of medium entering the housing to reverse the direction of movement of said valve stem.
